THREAD GUIDE

Michael J. McHale, Scranton, Pa.

Application July 20, 1934, Serial No. 736,247

9 Claims. (Cl. 242—157)

My invention relates to thread guides for winding machines and more particularly to means for mounting and attaching a guide eye to its support.

5 In application, Serial No. 708,480, filed January 26, 1934, now Patent 1,965,044, issued July 3, 1934, I have disclosed a thread guide fastening means in combination with a faller arm structure, wherein the guide may be easily and quickly replaced without the use of any special tool. The present invention is an improvement over the arrangement disclosed in the above referred to application and relates to a thread guide fastening device of general application with winding 10 machines and various attachments used therewith.

An object of my invention is to provide a fastening means for thread guides whereby the guide eye may be readily attached or detached 20 from its support arm or bracket.

Another object of my invention is to provide an improved locking means for the guide fastening device whereby the guide is held in tight engagement with its support.

25 Still another object of my invention is to provide an improved thread guide eye adapted to be used in combination with various types of winding machine structures and attachments used therewith.

30 With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

35 In order to make my invention more clearly understood, I have shown in the accompanying drawing means for carrying the same into practical effect, without limiting the improvements in their useful applications to the particular constructions, which for the purpose of explanation, 40 have been made the subject of illustration.

In the drawing:

Figure 1 is an elevational view of a thread cleaning device showing one form of my thread 45 guide attaching device.

Figure 2 is a plan view of Figure 1.

Figure 3 is a plan view of a modified form of the thread guide mounting arrangement shown in Figure 1.

50 Figure 4 is a side view of Figure 3.

Fig. 5 is a plan view of a modified form of the fastening device.

Fig. 6 is a side view of Figure 5.

Fig. 7 is an elevational view of another modified form of the invention.

Fig. 8 is a plan view of a modification of the fastening device.

Fig. 9 is a side view of Fig. 8.

Fig. 10 is a modification of the arrangement shown in Fig. 8; and

Fig. 11 is a perspective view of the thread guide holding means.

Referring to the drawing and more particularly to Figures 1 and 2 thereof, there is shown a thread cleaner comprising a body portion 1 having arms 2, 2' extending outwardly therefrom and a conventional blade support member, through which the thread 3' passes. Each arm is provided with a thread guide support member 4 adapted to thread into the arm and held in position on the arm by means of suitable lock nuts 5. The support member is threaded as at 6 and is further provided with a head 7 having an opening 8 formed therein. Attached to the end 9 of the support member is a thread guide 10 designated generally by numeral 10, formed with a longitudinal recess 11, a recess 12 extending perpendicular to the longitudinal recess and a groove 13 at the rear thereof, parallel to opening 12.

In order to maintain the thread guide 10 in fixed position on the support member 4, there is provided a looped member 14 having one end 15 threaded through the opening 8 formed in the head 7 of the support member, the other end 16 of said looped member seating in recess 12 formed in the body of the guide. The loop member may be in the form of wire and it is bent as at 17 to provide a spring action when the ends of the wire are inserted in the respective openings. It 40 will be noted that portion 18 of the wire seats in the groove 13 formed at the rear of the thread guide, the purpose of this arrangement being to prevent lateral movement of the guide with respect to its support.

45 In mounting the guide, loop member 14 is rotated away from the end of the support member so that the thread guide will clear the end of the wire when the recess portion 11 receives the end 9 of the support. After the guide is placed in position on the end of the support, end 16 of the wire is inserted into recess 12 formed in the body of the guide, portion 18 of the wire seating in the groove 13 formed at the end of the guide.

50 Referring to Figures 3 and 4, there is shown a

modification of the invention adapted to be used for mounting and supporting a thread guide on the frame or other parts of a winding machine. In this arrangement, the support comprises a 5 threaded member which may be in the form of a wood screw 19 having a flat substantially rectangular shaped head 20 having an opening 20' formed therein. Thread guide 10 is provided with an opening 21 adapted to receive one end 22 of 10 the loop member used in fastening the guide to the support. The guide is also provided with a longitudinal recess 23 in which the head 20 of the support 19 seats, and a groove 24 which forms 15 a seat for the straight portion 25 of the loop member when the guide is attached to the support.

Referring to Figures 5 and 6, there is shown a further modification of the arrangement disclosed in Figure 3, wherein the support member is 20 in the form of a machined screw. The purpose of this arrangement is to enable the support to be readily attached to metallic portions of a winding machine, the support being held in position on the machine by means of suitable lock 25 nuts. The thread guide and locking means for the guide together with the head portion of the support member are similar to the structure disclosed in Figure 3.

Referring to Figure 7, I have shown another 20 modified form of the improved thread guide support and locking means therefor, comprising a bolt 26 having a head 27 formed with a slot 28. The bolt is provided with a longitudinal recess 29 adapted to receive the end 30 of the looped 35 member 31. In this arrangement, the thread guide 10 is held in position on the end of the bolt by means of looped member 31, one end 32 of which passes through opening 33 formed in the body of the guide, the other end of the looped 40 member being bent around so that a portion 34 seats in the slot 28, the end 30 resting in the recess 29 formed in the body of the bolt.

Referring to Figures 8 and 9, there is shown a further modification of the thread guide mounting comprising a bolt 35 formed with a shou- 45 dered portion 36 and a flat projection 37. The thread guide is held in position on the bolt by means of a spring clip member provided with arms 38, 38'. As more clearly shown in Figure 8, the clip member is provided with an intermediate 50 portion 39 having an opening 40 adapted to receive the end of the bolt. In the arrangement shown in Fig. 9, the guide is formed with a longitudinal recess to accommodate projection 37, 55 and is held in the operative position on the bolt by means of the clip, arms 38, 38' of which engage with the body of the guide.

Referring to Figure 10, I have shown a modification of the arrangement shown in Figure 8, 60 wherein the clip is held in position on the bolt by means of a jam-nut 41. In this form of the device the thread guide seats on the head portion 42 of the bolt, the body of the guide being securely clamped between the arms of the clip.

While I have shown and described the preferred embodiment of my invention, I wish it to be understood that I do not confine myself to the precise details of construction herein set forth, by way of illustrations, as it is apparent 70 that many changes and variations may be made therein, by those skilled in the art, without departing from the spirit of the invention, or exceeding the scope of the appended claims.

I claim:

1. In a thread guiding device for winding ma-

chines, the combination of a guide support having an opening formed therein, a guide eye attached to the support comprising a body portion having a thread receiving opening, a recess longitudinal of the body forming a seat for one end of the guide support, a second recess extending through the body of the guide and means to lock the guide to the support, comprising a looped member, one end of which is threaded through the opening formed in the support, the other end being seated in said second recess formed in the body portion of the guide. 5

2. In a thread guiding device for winding machines, the combination of a guide support, a guide eye mounted upon said support, comprising a body portion having a thread receiving opening, a recess longitudinal of the body forming a seat for one end of the guide support, a second recess extending through the body of the guide perpendicular to said longitudinal recess, a groove formed in the guide at the end opposite the thread receiving opening, and means to lock the guide to the support comprising a looped member, one end of which is attached to the support, the other end being seated in said second recess formed in the body of the guide, a portion of said looped member intermediate of its ends, being seated in the groove at the rear of the guide whereby lateral movement of the guide 15 with respect to the support is prevented. 20

3. In a thread guiding device for winding machines, the combination of a guide support comprising a bolt, including a head portion having an opening formed therein, a guide eye mounted upon said support comprising a body portion having a thread receiving opening, a recess longitudinal of the body forming a seat for one end of the bolt, a second recess extending through the body of the guide perpendicular to said longitudinal recess, and means to lock the guide to the bolt comprising a looped member, one end of which is threaded through the opening formed in the head of the bolt, the other end being seated in said second recess formed in the body portion of the guide. 35

4. In a thread guiding device for winding machines, the combination of a guide support comprising a bolt, including a head portion having an opening formed therein, a guide eye mounted upon said support comprising a body portion having a thread receiving opening, a recess longitudinal of the body forming a seat for one end of the bolt, a second recess extending through the body of the guide perpendicular to said longitudinal recess, a groove formed in the guide at the end opposite the thread receiving opening and means to lock the guide to the bolt comprising a looped member, one end of which is threaded through the opening formed in the head of the bolt, the other end being seated in said second recess formed in the body portion of the guide, a portion of said looped member intermediate of its ends being seated in the groove at the rear of the guide whereby lateral movement of the guide with respect to the support is prevented. 40

5. In a thread guiding device for winding machines, the combination of a guide support comprising a screw threaded member, including a flat head portion having an opening formed therein, a guide eye mounted upon said support comprising a body portion having a thread receiving opening, a recess longitudinal of the body forming a seat for the flat head portion of the support, a second recess extending through the body of the guide perpendicular to said longitudinal 45 recess, a groove formed in the guide at the end opposite the thread receiving opening and means to lock the guide to the bolt comprising a looped member, one end of which is threaded through the opening formed in the head of the bolt, the other end being seated in said second recess formed in the body portion of the guide, a portion of said looped member intermediate of its ends being seated in the groove at the rear of the guide whereby lateral movement of the guide with respect to the support is prevented. 50

nal recess and means to lock the guide to the support comprising a looped member, one end of which is threaded through the opening formed in the head of the screw threaded member, the 5 other end being seated in said second recess formed in the body portion of the guide.

6. In a thread guiding device for winding machines, the combination of a guide support comprising a screw threaded member including a 10 flat head portion having an opening formed therein, a guide eye mounted upon said support comprising a body portion having a thread receiving opening, a recess longitudinal of the body forming a seat for the flat head portion of the support, a second recess extending through the body 15 of the guide perpendicular to said longitudinal recess, a groove formed in the guide at the end opposite the thread receiving opening and means to lock the guide to the screw threaded member 20 comprising a looped wire, one end of which is threaded through the opening formed in the head of the bolt, the other end being seated in said second recess of the body portion of the guide, a portion of said wire intermediate of its ends 25 being seated in the groove at the rear of the guide whereby lateral movement of the guide with respect to the support is prevented.

7. In a thread guiding device for winding machines, the combination of a guide support comprising a bolt, having a longitudinal recess formed in the body portion thereof, the guide eye mounted upon said support comprising a body portion having a thread receiving opening, a re- 30

cess longitudinal of the body forming a seat for one end of the bolt, a second recess extending through the body of the guide perpendicular to said longitudinal recess, and means to lock the guide to the bolt comprising a looped member, one end of which is seated in the longitudinal opening formed in the body portion of the bolt, the other end being seated in said second recess formed in the body portion of the guide. 5

8. In a thread guiding device for winding de- 10 vices, the combination of a guide support comprising a bolt having a flat shouldered portion, a guide eye attached to the bolt and seated against said shouldered portion comprising a body portion having a thread receiving opening and means 15 to maintain the guide in operative position on the support, comprising a clip member attached to said support and formed with spring arms adapted to clamp the guide therebetween. 10

9. In a thread guiding device for winding ma- 20 chines, the combination of a guide support comprising a bolt having a shouldered portion and a projection extending beyond the shouldered portion, a guide eye mounted upon the bolt comprising a body portion having a thread receiving 25 opening, a recess longitudinally of the body forming a seat for the projection formed on the support and means to maintain the guide on the support comprising a clip member attached to the support and formed with spring arms adapted to 30 clamp the guide therebetween. 25

MICHAEL J. McHALE.
